(57) **CLAIM**

The ornamental design for an interface of a magnetic disc storage, as shown and described.

DESCRIPTION

FIG. 1 is a front, and right side perspective view of an interface of a magnetic disc storage showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a sectional view thereof taken in the direction of the arrows 8—8 in FIG. 2; and,

FIG. 9 is a sectional view thereof taken in the direction of the arrows 9—9 in FIG. 2.

The broken lines are shown in the views for illustrative purposes only and form no part of the claimed design. The internal portions of the interface form no part of the claimed design.
